UNITED STATES PATENT OFFICE.

JOUZAS KARASEVICZ, OF SOUTH AMBOY, NEW JERSEY.

COMBINATION GUN AND WIRE-CUTTER.

1,302,668.

Specification of Letters Patent.

Patented May 6, 1919.

Application filed August 12, 1918. Serial No. 249,384.

To all whom it may concern:

Be it known that I, JOUZAS KARASEVICZ, a citizen of Russia, residing at South Amboy, county of Middlesex, and State of New Jersey, have invented certain new and useful Improvements in Combination Guns and Wire-Cutters, of which the following is a specification.

This invention relates to improvements in devices for cutting entanglements such as wire fences and like constructions as erected by an enemy as used for warfare.

The principal object of the invention is to provide an implement mounted upon a truck so that it may be readily transported and carrying a pair of parallel guns adapted to simultaneously propel projectiles, having arranged between them a cutting blade so as to demolish the entanglement and provide an opening through which soldiers may pass.

A further object is to provide means whereby a pair of twin guns may be rotated upon a central axis so that the cutter blade may be discharged either vertically, horizontally or at an angle therebetween.

These and other like objects, such as means for rotating and discharging the guns and applying cutters are obtained by the novel construction and combination of parts hereinafter described and shown in the accompanying drawings, forming a material part of this disclosure, and in which:

Figure 1 shows a side elevational view of an implement made in accordance with the invention.

Fig. 2 is a fragmentary top plan view of the same.

Fig. 3 is a front elevational view thereof.

Fig. 4 is a perspective view showing one of the projectiles used, and

Fig. 5 is a perspective view showing a cutter blade as used when engaged with the projectile.

Referring to the drawings, a platform 10 provided with supports 11, is mounted upon axles 12, journaled in wheels 13 and forming an ordinary type of truck.

Fixed upon the upper surface of the platform 10, at the front, is a bracket 15 having a bent arm 16 extending centrally of and to some distance above the top of the platform, and mounted therein is the cylindrical end 17 of a rectangular bar 18 the opposite end being fitted to rotate in a similar bracket, 19, also secured to the platform.

Near the outer extremity of the extending

end 20 of the bar 18, is mounted a spur gear 22, connecting with another gear 23, fixed upon a spindle 24 journaled in the upper ends of a double bracket 25 secured to the platform 10, the spindle 24 being at one side of and below the axial center of the bar 18.

This spindle is adapted to be rotated by a lever 26, having an actuating handle 27 and through the gear connections the bar may be rotated.

Secured upon the bar 18, on each side of the bracket 19, are a pair of arms 28 connected by cross bars 29 and extending through the arms 28 are firing rods 30 having sharp conical points 31.

A portion of the rods 30 extend rearwardly and are surrounded by coiled tension springs 32, one of the ends of the springs being secured to rear of the arm 28 while the opposite, outer ends of the springs are secured in a like manner to a cross bar 33 in which the rear ends of the rod are firmly engaged.

Set in the outer side of the cross bar 33 is an eye 34 and loosely engaged therein is an open link or loop 35 engaging with a hook shaped point 36 formed with a segment 37, pivoted upon a pin 38, in a lever 40, which in turn is pivoted on a pin 41 to a bracket 42, secured centrally of the rear end of the platform 10.

The lever 40 is provided with an extending handle 43 and has formed on its outer side a lug 44 containing an opening through which passes a pin 45 the same acting as a fulcrum for the detent lever 46, having an operating handle 47 at its upper end, while the lower end has a recess 48 adapted to engage with the opposite corner of the segment 37, a spring 49 normally holding the detent lever 46 in an engaged position in reference to the segment, the construction being such that when the lever 40 is drawn rearwardly, as to cause the rods 30 to be retracted, tensioning the springs, 32 which may be released by operating the lever 46 so as to drive the points 31 simultaneously and forcibly forward in an obvious manner.

Secured upon the front end of the square bar 18 are a pair of supports 52 adapted to hold the guns 53 in parallel spaced relation, these guns being provided with a block or cap 54 secured on one side by the hinge 55 and at the other side by latch clips 56 pivoted on pins 57 to the body of the gun, the clips having hooks 58 engageable with

pins 59 fixed in the sides of the caps 54, the caps being provided with central circular apertures adapted to receive the pointed ends of the rods 30, as they are impelled forward, 5 due to the action of the springs 32.

Formed lengthwise through the muzzles of the guns are elongated slots 60 extending completely through from side to side, the slot in one gun being in the same plane as 10 the slot in the other while the guns contain a single rifling slot parallel with the axis thereof and suited to receive the keylike projections 62 formed on the heads 63 of projectiles 64 the heads having single apertures 15 65 receptive of fulminating caps adapted to be detonated by contact with the points 31 of the firing rods.

The reduced front ends 66 of the projectiles terminate in acutely formed conical 20 points 67 and adjacent to the bases of the conical points 67 are two openings 68, receptive of a knife or cutter blade 70 which is also adapted to be received within the slots 60, the blades being fashioned with an 25 acute cutting edge 71 along the major portion of their length, the lower ends being adapted to extend into one of the rectangular openings 68 of the projectile, as at 72, and provided with extending lugs 73 which 30 are adapted to seat against the surface of the solid portions 66 of the projectiles so as to be held in engagement thereby.

From the foregoing it will be understood that the projectiles are first entered within 35 the breech of the gun, the cutter bar 70 entered through one side of the gun, passed through the projectile therein and then into the oppositely disposed gun, into the position as shown in Fig. 1.

40 By retracting the lever 40 and suddenly

permitting it to rebound, under the effect of the springs 32, the projectiles are discharged simultaneously from the muzzles of the guns carrying the cutter bar 70 engaged 45 between them.

Due to the action of the crank 26 it will be obvious that the entire mount may be rotated upon the axis of the horizontal shaft 18 so that the projectiles can be discharged in any desired plane whatever, and obviously, due to the cutter bar 70, any ordinary fence or wire entanglement may be so broken or destroyed as to admit passage therethrough.

Having thus described my invention and 55 set forth the manner of its construction and use what I claim as new and desire to secure by Letters Patent, is—

In an implement of the class described, the combination with a wheeled platform, 60 brackets arranged on the upper surface thereof, a bar pivotally mounted in said brackets, a pair of guns operatively connected at the sides of said bar, firing pins secured to said bar at the end thereof, means 65 for manually rotating said bar, an elongated slot passing through the muzzles of said guns, projectiles fitted to the bore of said guns, said projectiles having a transverse passage formed therethrough, a cutter bar 70 engageable in said transverse passages movable in the slots in the muzzles of said guns, means for rotating said guns upon the axis of said bar into different planes, said firing 75 means moving therewith, and means for operating said firing means whereby said projectiles may be simultaneously discharged.

In testimony whereof I have affixed my signature.

JOUZAS KARASEVICZ.
